Primary Examiner — Manpreet Matharu*Assistant Examiner* — Keith Wilson(74) *Attorney, Agent, or Firm* — Mickki D. Murray, Esq.; Parks IP Law LLC(57) **CLAIM**

We claim the ornamental design for an upper vehicle grille, as shown and described.

DESCRIPTION

FIG. 1 is a front perspective view of an upper vehicle grille showing the new design;

FIG. 2 is a top view, thereof;

FIG. 3 is a front view, thereof.

In the figures, the broken lines shown illustrate portions of the upper vehicle grille that form no part of the claimed design.
